UNITED STATES PATENT OFFICE.

LOUIS M. BROWN, OF BEVERLY, AND ALBERT A. MACLEOD, OF SWAMPSCOTT, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY.

WORK-SUPPORT FOR SHOE-MACHINES.

1,295,963,

Specification of Letters Patent.

Patented Mar. 4, 1919.

Application filed June 23, 1915. Serial No. 35,816.

To all whom it may concern:

Be it known that we, LOUIS M. BROWN and ALBERT A. MACLEOD, citizens of the United States, residing at Beverly and 5 Swampscott, respectively, in the county of Essex and State of Massachusetts, have invented certain Improvements in Work-Supports for Shoe-Machines, of which the following description, in connection with the 10 accompanying drawings, is a specification, like reference characters on the drawings indicating like parts in the several figures.

This invention relates primarily to work supports for shoe machines and is herein 15 shown as embodied in work positioning means particularly adapted for use in machines which operate to trim the edge of an insole after the insole is attached to a last.

In the manufacture of some types of shoes, 20 such as welt shoes, it is the usual practice, after the insole is attached to the bottom of the last, to trim the heel portion of the insole to the edge contour of the heel seat of the last. A machine for this purpose forms 25 the subject-matter of United States Patent No. 1,076,431, granted October 21, 1913 on the application of E. L. Keyes. The insole is attached to the last usually by means of a plurality of tacks driven along the middle 30 of the forepart and shank and by a single tack at the heel seat driven into the last through an opening in the metal anvil plate with which the heel end of a last is usually provided. The tacks along the forepart and 35 shank may be driven at random, but the heel seat tack must enter the comparatively small opening in the anvil plate. As a result the material of the last where the heel seat tack is driven is worn away with comparative 40 rapidity so that finally a tack driven at this point fails to hold the heel portion of the insole securely. There are in use, moreover, in the manufacture of some classes of shoes, lasts in which no opening is provided in the 45 metal anvil plate for the reception of a tack and in which it is not desirable to provide such an opening lest the strength of the plate be weakened unduly.

The machine shown in the patent above referred to includes a yielding presser mem-

ber for engaging the bottom face of the insole close to the point of operation of the cutter to prevent the insole from being deflected by the cutter in such a manner as to be trimmed unevenly. While this arrangement has proved to be satisfactory in operation under the usual working conditions, it is not always sufficiently effective where the insole is insecurely tacked at the heel seat or where there is no heel seat tack. This arises largely from the fact that during the trimming operation there is rubbing engagement between the presser member and the insole which tends to neutralize to some extent the clamping effect of the presser member.

An important object of this invention accordingly is to provide for use in a machine for trimming an insole attached to a last improved means for positioning the insole in relation to the last. To this end a feature of the invention consists in a novel construction and arrangement of work positioning means including a clamp member arranged to engage the bottom face of the insole and to turn with the last during the trimming operation, this member, in the illustrated construction, being movable relatively to the last in engaging or releasing the insole. As a further feature also the invention provides means convenient for manipulation by the operator to enable him to effect and maintain engagement of the clamp member with the insole, without interfering with such movements of the work support and the last as are necessary in order to present different portions of the edge of the insole in position to be trimmed. The construction shown includes a hand lever for controlling the clamping or unclamping of the insole, this lever being mounted upon the movable work support convenient to that hand of the operator by which he moves the support toward or from the trimming cutter, thus leaving his other hand free to manipulate the last in the customary manner.

A further feature of the invention consists in a work support for shoe machines including provision for bodily movement of a last, and means for clamping shoe stock.

upon the bottom of the last arranged to be moved to operative position through said movement of the last.

Another feature of the invention consists in a rotatable last support and means for maintaining it when idle in a position convenient for the reception of a last.

Still another feature consists in a last support having novel means for engaging the sides of the last to position it upon the support. The construction shown includes members movable to engage opposite sides of the neck of a last combined with means for applying pressure upon the bottom of the last arranged to cause said members to be moved inwardly toward the last upon the application of pressure to the last bottom.

The invention also includes, as a further feature, a swinging work support, and novel means tending to counterbalance the support so as to facilitate manipulation of the work. The invention also includes a novel construction for supporting the edge of the insole adjacent to the point of operation of the cutter, and a novel combination of operating and supporting instrumentalities comprising a clamp member for firmly positioning an insole on a last.

The above and other features of the invention, including certain details of construction and combinations of parts, will now be described with reference to the accompanying drawings, which illustrate a preferred embodiment of the invention, and will be pointed out in the claims.

Although the invention is illustrated herein in its application to a machine for trimming an insole attached to a last, it will be understood that in its broader aspects the invention is not thus limited but is applicable in many of its features to use with different classes of shoe machines for performing various operations in shoe manufacture.

In the drawings, Fig. 1 is an end view in elevation of an insole heel seat trimming machine similar to that shown in the patent hereinbefore referred to, including novel work positioning means in which the present invention is embodied;

Fig. 2 is a perspective view of the novel work positioning means as viewed diagonally from the left with reference to Fig. 1;

Fig. 3 is a view in section through the cutter and adjacent portions of the illustrated machine showing the manner in which the work is presented for treatment;

Fig. 4 shows in elevation, and partly in section, a portion of the mechanism including the connections between the last support and the insole clamping member, showing the parts in a different position from that illustrated in Fig. 2 and with portions of the mechanism omitted for the sake of clearness in the illustration;

Fig. 5 is a plan view, partly in section, of the mechanism for controlling the clamping of the insole, showing the parts in a different position from that illustrated in Fig. 2;

Fig. 6 is a view partly in vertical section in the plane of Fig. 1, illustrating in detail a part of the connection between the upright arm of the work support and the work supporting head, and

Fig. 7 is a front elevation of the lower portion of the work supporting means.

The machine illustrated in Figs. 1 and 3 comprises a frame 2 having bearings for a rotary shaft 4 which carries a toothed cutter 6 and the usual shield 8.

Positioned at the end of the cutter is a guide member 10 constructed for engagement with the lateral surface of a last, as *a*, adjacent to the edge of the heel seat to guide the last in its turning movement during the operation of trimming around the edge of the heel portion of the insole *b*, this guide member having a lip 12 to project between the bottom of the last and the insole for the purpose of positioning the last axially of the cutter and supporting the insole out of contact with the last adjacent to the point of operation of the cutter, as well as preventing any possible engagement of the cutter with the last, all as more fully explained in the patent hereinbefore referred to. The guide member 10 is mounted adjustably in a support 14 which is pivoted to the frame 2 at 16 to permit the member to be swung away from the cutter when it is desired to remove the cutter from its shaft. Mounted upon the shaft 4 also to rotate therewith is a presser member 18 which is movable lengthwise of the shaft and during the trimming operation is held by means of a light spring 20 against the insole adjacent to the point of cut to assist in preventing the insole from bending away from the cutter. This member is preferably formed as a spider with its arms extending inwardly between the teeth of the cutter (see Fig. 3) and across the edge of the insole being trimmed. A collar 22 secured to the shaft by a screw 24 that projects through a slot 26 in a sleeve 28 extending from the member 18 serves as an abutment for the spring 20 and by engagement with the inturned end of the sleeve determines the idle position of the presser member 18 so as to permit the insole to force the member back slightly in opposition to the spring 20 when the insole is presented to the cutter.

Secured upon one side of the lower portion of the frame 2 is a bracket 30 provided with a horizontal arm 32 upon which the work support of the machine is mounted. This arm is provided at its outer end with a bearing 33 for the reception of a stem 34 which projects from a block 36. The block 36 is thus permitted to turn with reference

to the arm 32 within limits determined by a stop 38 upon the arm with which the block is arranged to engage. Projecting from the block 36 at right angles to the stem 34 is a rod 40 which provides a bearing for the upwardly extending arm 42 of the work support. Mounted upon the upper end of the arm 42 is a head 44 having a stem 46 which engages in a bore in an offset portion of the arm so that the head may turn to a limited extent in a plane transverse to the arm. The head 44 has depending therefrom a pin 48, Fig. 6, which enters a recess 50 formed in the upper end of the arm 42, and threaded through the arm at opposite sides are screws 52 the inner ends of which extend into the recess 50 and serve by engagement with the pin 48 to limit adjustably the turning movement of the head 44 in both directions about the axis of the stem 46. The purpose of such turning movement of the head 44 will be hereinafter explained. Secured in a bore in the head 44 is a sleeve 54 through which extends a spindle 56 the forward end portion of which is arranged to enter the last pin socket of a last as shown in Fig. 2. The spindle 56 is free both to move endwise and to turn within the sleeve. The sleeve 54 is extended at one side of the head to provide a bearing for a bracket 58 which is mounted thereon for rotation about the axis of the spindle 56, the sleeve having a flange 59 at its outer end to retain the bracket in position thereon, as shown in dotted lines in Fig. 2. Secured to the spindle 56 at a distance from its forward end is a plate 60 which is formed with grooves 62 to provide a slideway for a pair of last positioning members 64, these members being movable upon the slideway toward and from the spindle 56. The members 64 comprise a pair of jaws arranged for engagement with the sides of the neck portion of a last to assist in maintaining the last firmly in position upon its support. Pivoted on one side of the plate 60 are bell crank levers 66 in one arm of each of which is formed a slot for the reception of a pin 68 which projects from the corresponding jaw 64, as shown in Fig. 2. A spring 70 is connected to the levers 66 in such manner as to cause the jaws 64 to be separated as far as permitted by pins 72, the outer ends of which are seen in Fig. 2, these pins projecting at their inner ends in position to be engaged by the jaws 64 in their outward movement, as will be readily understood. The other arms of the levers 66 project inwardly in position to be engaged by the neck of the last when the last is mounted upon the spindle. It will thus be seen that when a last is mounted upon the spindle and is moved to cause the spindle to approach the bottom of the last pin socket, the levers 66 will be engaged by the last and swung about

their pivots, thus causing the jaws 64 to slide inwardly and make firm contact with the sides of the neck portion of the last so as to prevent the last from tipping and assist in maintaining it in fixed relation to the spindle during the trimming operation. 70

From a consideration of the construction as thus far described it will be seen that after a last has been positioned upon the forward end portion of the spindle 56, endwise movement of the spindle, which carries the other portions of the last support including the plate 60 and the jaws 64, will serve to effect displacement of the last transversely of the plane of its heel seat portion, 75 and during such movement the last is carried from or toward the bracket 58 which is restrained from similar movement by the head 44 and the flanged end 59 of the sleeve 54. Extending from the plate 60 are pins 80 74 which are arranged for sliding engagement in recesses in the bracket 58 as the plate is moved toward or from the bracket by endwise movement of the spindle 56, this arrangement serving to maintain the bracket 90 58 and the last support in the same angular relation with reference to rotation about the axis of the spindle 56 so that the bracket and the support must rotate in unison.

The means for clamping the insole upon 95 the last comprises mechanism mounted upon the bracket 58, and including a member 76 which is arranged for sliding movement in substantially parallel relation to the spindle 56. Secured upon the slide 76 by means of a 100 thumb screw 78 is an arm 80 which is formed to extend down the side of the last forwardly of the heel portion and is bent to extend inwardly over the last bottom to substantially the longitudinal median line of the last. This 105 arm carries a clamp member 82 which extends therefrom toward the rear of the heel seat and has a plurality of pointed pins 84 for effecting secure engagement with the insole. The member 82 is formed of slightly 110 resilient material and is inclined somewhat with reference to the plane of the last bottom, as shown in Fig. 3, so as to permit the clamping device to be manipulated readily notwithstanding slight variations in the 115 thickness of different insoles or the height of different lasts. By means of a screw and slot connection 86 the clamp member is adjustable with reference to the arm 80 to vary the position of its insole engaging portion 120 with reference to the rear end of the heel seat, particularly for the purpose of accommodating the device to lasts of different styles and sizes. The arm 80 has a slot 88 in which is received a projection 90 of the slide 76 to 125 maintain the arm in the same angular relation to the slide and permit the arm to be adjusted lengthwise of the slide to adapt the device for considerable variations in the height of different styles or sizes of lasts. 130

Pivoted at 92 upon the bracket 58 is a lever 94, the opposite end portions of which are connected by means of links 96 and 98 respectively with the slide 76 and the plate 60 of the last support. It will be readily seen that with this arrangement endwise movement of the spindle 56 in either direction will cause the slide 76 and the clamp member 82 to move in the opposite direction. A spring 100 connected at one end to the slide 76 and at its other end to a portion of the bracket 58, as seen in Fig. 4, tends to maintain the clamping device and the last support in positions in which the clamp member 82 is relatively remote from the end of the spindle 56 so as to permit a last to be readily mounted upon the spindle without interference from the clamp member.

The operating means for effecting the clamping of the insole comprises a lever 104 pivoted at 102 to the head 44, and connected by links 106 with a bar 108 which is mounted loosely upon the spindle 56 between collars 110 on the spindle. Between the bar and the forward collar 110 is a ball bearing 112 which is arranged to facilitate the rotation of the spindle through the turning movement of the last when the lever is held in position to effect the clamping of the insole. With this device the operator can readily effect with one hand such relative movement of the last support and the clamp member as to clamp the heel portion of the insole securely in position upon the last and position the last firmly upon its support for the trimming operation. A grip member 114 on the head 44 assists the operator in operating the lever and in maintaining it in position to clamp the work while the work positioning means, including the last support and the clamping device, are rotated through the turning movement of the last which is effected by the other hand of the operator.

In order to maintain the work positioning means when idle in a position convenient for the reception of a last, the bracket 58 is provided with a weight 116 which tends to occupy the position shown in Figs. 1 and 2, thus presenting the last support in such relation to the operator that he may conveniently mount a last upon the spindle 56 between the members 64 while holding the last by the forepart in the usual manner. In order to prevent the bracket 58 and the parts which are rotatable therewith from swinging unduly upon the removal of a last from the spindle and further to insure that the last support shall be maintained in a position convenient for the reception of a last, the head 44 is provided with a slot 118 and the pins 74 are of such length that their end portions are caused to enter this slot as the last support moves toward the bracket under the influence of the spring 100. Should the bracket start to swing when the work is re-

moved, the pins will readily engage in the slot 118 and lock the bracket against further movement until it has been released by the manipulation of the lever 104.

It will be seen that by reason of the arrangement of the rods or spindles 34 and 40 the work support is afforded a substantially universal swinging movement to facilitate the presentation of the work to the machine and that the weight of the support will tend to swing it toward the front and toward one side of the machine about the respective axes 40 and 34. In order partially to counterbalance the support and assist in presenting the work to the machine, the arm 42 has an extension 120 which projects rearwardly and to the opposite side with reference to the respective axes 40 and 34 and carries a plunger 122 which is arranged to engage the lower side of the arm 32 and is operated by a spring 124 so as partially to counterbalance the work support in its tendency to swing both toward the front and the side of the machine. The tension of the spring 124 may be varied by means of a screw 126.

In addition to the substantially universal swinging movement of the work support, by reason of the manner in which the arm 42 is mounted upon the supporting bracket 32, the head 44, as hereinbefore explained, is permitted to turn relatively to the arm 42 within the limits set by the screws 52. This arrangement affords provision for such angular variation between the axis of turning movement of the last and the axis of the cutter as is desirable in order to permit the insole to be trimmed to the edge of the last bottom on lasts of different shapes.

It will be evident from the preceding description that the operator may manipulate the work support to carry the work toward or from position to be operated upon by the machine and may also manipulate the lever 104 to effect the clamping or releasing of the insole by the use of one hand, thus affording him the free use of his other hand to mount the last upon the support or to remove it therefrom and to turn the last to cause the cutter to trim around the heel seat. With the parts in their idle positions it is only necessary, in order to position the work, to mount a last upon the end of the spindle 56 and to swing the lever 104 toward the grip member 114, thus moving the last toward the clamp member 82 and simultaneously moving this member toward the last bottom to effect the clamping of the insole. As pressure is applied upon the insole by the member 82, the last will be forced farther inward upon the spindle and the jaws 64, through the operation of the levers 66, will be caused to press upon the neck of the last at opposite sides to hold it firmly in position. Movement of the lever simultaneously unlocks the bracket

58 by withdrawing the ends of the pins 74 from the slot 118, as previously explained. The operator then swings the work support to carry the insole toward the 5 cutter, this swinging movement being assisted by the operation of the spring plunger 122. When the parts have been positioned in operative relation to the cutter, as shown in Fig. 3, the last is turned to 10 cause the cutter to operate around the heel seat upon all portions of the edge of the insole which it is required to trim, the last support and the clamp member and their connections, together with the bracket 58, 15 being arranged to turn with the last, and relatively to the lever 104, in the manner previously explained. When the support is swung away from the cutter and the lever 104 is released, the spring 100 immediately 20 returns the parts to their idle positions, thus releasing the work and permitting the last to be removed from the spindle.

It will be seen by reference to Fig. 3 that the presser member 18 constructed and positioned as shown and described presents no obstruction to the clamping device during the manipulation of the work and by pressure upon the insole adjacent to the point of cut assists in preventing the insole from 30 being deflected by the cutter. It will also be readily understood that the arm 80 and other portions of the clamping device constructed as shown and described oppose no obstruction to the cutter in performing the 35 usual trimming operation required in order to conform the heel portion of the insole to the contour of the edges of the heel seat of the last.

Although the invention has been disclosed as embodied in mechanism having the details of construction shown and described, it will be understood that the invention is not thus limited in its application but is susceptible of various embodiments within 40 the spirit and scope of the appended claims.

Having described the invention, what we claim as new and desire to secure by Letters Patent of the United States is:—

1. In a machine for trimming an insole 50 attached to a last, the combination of supporting means for the last constructed to permit the last to be moved to bring different portions of the edge of the insole into position to be trimmed, and a device constructed to engage the bottom face of the insole in a location remote from the edge to be trimmed to hold the insole from slipping on the last, said device being movable with the last during the trimming operation 55 and movable also relatively to the last to permit the last to be removed from its supporting means.

2. In a machine for trimming an insole 60 attached to a last, the combination of supporting means for the last mounted for

turning movement with the last to bring different portions of the edge of the insole into position to be trimmed, a device movable relatively to said supporting means to engage the heel seat of the insole in a location remote from the edge of the heel seat to prevent the heel portion of the insole from slipping on the last, and connections between said device and the last supporting means to cause the device to turn with said means. 70

3. In a machine for trimming an insole attached to a last, a work support movable to carry the work bodily to different positions in the machine and having means 80 for supporting a last for turning movement to bring different portions of the edge of the insole into position to be trimmed, a device carried by said work support for engaging the bottom face of the insole to hold 85 the insole in position upon the last during the trimming operation, said device being mounted to turn with the last and movable also in invariable relation to the axis of turning movement of the last to engage the 90 insole or to permit the last to be removed from the support, and means comprising a hand lever mounted on the support for effecting engagement of said device with the 95 insole.

4. In a machine for trimming to the contour of the heel end of a last the heel portion of an insole on the bottom of the last, the combination with last supporting means, of means for engaging and holding the heel 100 portion of the insole in position upon the last comprising a device arranged to extend from one side of the last over the edge of the last bottom in front of the heel portion of the insole and to extend thence rearwardly along the median line of the last bottom into position to engage the heel seat portion of the insole in a location remote from the rear edge of the heel seat. 105

5. In a machine for trimming to the contour of the heel end of a last the heel portion of an insole on the bottom of the last, the combination with a last supporting spindle, of means for engaging and holding the heel portion of the insole in position upon 110 the last comprising an arm arranged to extend at one side of the last in substantially parallel relation to said spindle and having an end portion formed to extend over the last bottom in front of the heel portion of 115 the insole, and a clamp member secured to said end portion of the arm and extending at an angle to the arm into position to engage the central portion of the heel seat of the insole remote from the edge to be 120 trimmed.

6. A device of the class described comprising, in combination, a last support, and a member for engaging and clamping shoe stock upon the bottom of a last on said sup- 130

port, said clamp member and support being connected to cause the one to be moved through movement of the other, to bring said member and the last into clamping relation.

7. A device of the class described comprising, in combination, a last support, and a member for engaging and clamping shoe stock upon the bottom of a last on said support, said clamp member and support being connected for simultaneous rectilinear movement from idle positions into coöperative relation for clamping the stock upon the bottom of the last, and means tending to maintain said member and support normally in their idle positions.

8. A device of the class described comprising, in combination, a last support movable to effect bodily displacement of the last, and means for clamping shoe stock upon the bottom of the last arranged to be moved to operative clamping position through said movement of the last support.

9. A device of the class described comprising, in combination, means for supporting a last and for moving it bodily in a direction transverse to the plane of its heel seat, means for clamping shoe stock upon the bottom of the last, and means connecting said clamping means and last supporting means to cause the clamping means to be moved to operative clamping position through said movement of the last supporting means.

35 10. A device of the class described comprising, in combination, a last support movable to effect displacement of the last in a direction transverse to the plane of its heel seat, a clamp member for engaging and clamping shoe stock upon the bottom of the last, said member being mounted for movement toward or from the last bottom in a path substantially parallel to the path of said movement of the last, and means connecting said clamp member and support to effect the movement of said member through the movement of the support.

11. A device of the class described comprising, in combination, a longitudinally movable spindle arranged for engagement in the last pin socket of a last, a clamp member for engaging shoe stock upon the bottom of a last on said spindle, and means connecting said spindle and clamp member to effect movement of said member to operative clamping position through movement of the spindle.

60 12. A last device of the class described comprising, in combination, a last supporting spindle, a clamp member positioned opposite to the end of said spindle for engaging and clamping shoe stock upon the bottom of a last on the spindle, operating means for imparting endwise rectilinear

movement to the spindle, and means connecting said operating means and the clamp member for moving said member toward or from the last in unison with said movement of the spindle.

13. A device of the class described comprising, in combination, a bracket, a last support movable relatively to said bracket to carry a last in directions transverse to the plane of the heel seat, a clamp member mounted on the bracket for engaging and clamping shoe stock upon the bottom of the last, said member being movable relatively to the bracket into or out of position to clamp the stock, and means connecting said clamp member and support for effecting said movements of the clamp member through movement of the support.

14. A device of the class described comprising in combination, a bracket, a spindle mounted for endwise movement in said bracket and having means for supporting a last, a slide mounted on the bracket, means carried by the slide for engaging and clamping shoe stock on the bottom of the last, and means connecting said slide and last supporting means for simultaneous movement in substantially opposite directions.

15. A device of the class described comprising, in combination, a bracket, a spindle mounted for endwise movement in said bracket and having means for supporting a last, a slide mounted on the bracket, means carried by the slide for engaging and clamping shoe stock on the bottom of the last, a lever pivoted between its ends on the bracket, and links connecting the ends of the lever respectively to the slide and the last supporting means to effect movement of the slide in a direction opposite to the direction of movement of said means.

16. A device of the class described comprising, in combination, a rotatable bracket, a last support mounted for rotation with the bracket, means carried by the bracket for engaging and clamping shoe stock upon the bottom of a last on said support, and mechanism for operating said clamping means comprising a manually operated member and means for maintaining operative connection between said member and clamping means while permitting the bracket to be rotated relatively to said member.

17. A device of the class described comprising, in combination, a supporting head, a bracket rotatable on said head, a spindle movable endwise through said bracket and head at the axis of rotation of the bracket and having means for positioning a last thereon, means carried by the bracket for engaging and clamping shoe stock on the bottom of a last on said spindle, connections between said clamping means and the spindle for operating said means through end-

- wise movement of the spindle, and a hand lever on said supporting head for effecting the movement of said spindle.
18. A device of the class described comprising, in combination, a supporting head, a rotatable last support mounted on said head, means rotatable with said support for engaging and clamping shoe stock upon the bottom of a last on the support, and mechanism for effecting relative movement of said support and clamping means into or out of coöperative relation to clamp the stock comprising a hand lever pivoted on said head and a grip member positioned adjacent to the lever to facilitate the manipulation of the lever.
19. A device of the class described comprising, in combination, a last support constructed to receive a last in a predetermined position thereon and rotatable to turn the last about an axis intersecting the bottom of the last, and means tending to maintain said support normally in a position of rotation about said axis convenient for the reception of a last.
20. A device of the class described comprising, in combination, a last support mounted for rotation about a substantially horizontal axis intersecting the heel seat of a last mounted thereon, and a weight tending to maintain said support normally in a predetermined position of rotation about its axis for the reception of a last.
21. A device of the class described comprising, in combination, a rotatable last support constructed to receive a last in a predetermined position thereon, and means for locking said support in a position of rotation about its axis convenient for the reception of a last.
22. A device of the class described comprising, in combination, a rotatable last support, means for rotating said support to bring it normally to a predetermined position of rotation about its axis, and means for locking the support in said position.
23. A device of the class described comprising, in combination, a rotatable last support, means for locking said support in a predetermined position of rotation about its axis, a clamp member for engaging and clamping shoe stock upon the bottom of a last on said support, and operating means for effecting relative movement of said support and clamp member to clamp the stock, said operating means being constructed and arranged to unlock the support during said movement.
24. A device of the class described comprising, in combination, a supporting head, a bracket rotatable on said head, a spindle mounted for endwise movement through said bracket and head and having last positioning means thereon, and a pin projecting from said means and movable endwise in a bore in the bracket, the supporting head having a slot to receive the end of said pin for preventing rotation of the last supporting means when the parts of the device are in idle positions.
25. In a shoe machine, work positioning means comprising relatively movable members for engaging the neck of a last at opposite sides to position the last, a clamp member for engaging shoe stock upon the bottom of the last, the last and the clamp member being movable relatively to cause the clamp member to press upon the stock, and means operated by said relative movement of the last and the clamp member for effecting pressure of said neck engaging members upon the last.
26. In a shoe machine, work positioning means comprising a last support constructed to position a last for turning movement, a clamp member for engaging shoe stock upon the bottom of a last on said support, said member being arranged to turn with the last and the member and support being relatively movable to clamp the last between them, a pair of jaws mounted upon the support at opposite sides of the neck of the last, and means operated by engagement with the last for effecting movement of said jaws toward the last.
27. In a shoe machine, work positioning means comprising a last support constructed to position a last for turning movement, a clamp member for engaging shoe stock upon the bottom of a last on said support, said member and support being relatively movable to clamp the last between them and movable in unison with the turning movement of the last, a pair of jaws mounted upon the support at opposite sides of the neck of the last for movement toward or from the last, means tending to move said jaws away from the last, and means operated by engagement with the last for moving the jaws toward the last.
28. In a shoe machine, work positioning means comprising a last spindle, a pair of jaws at opposite sides of the spindle for engaging and positioning the neck of the last, and a clamp member arranged to engage and hold shoe stock upon the bottom of the heel portion of the last, said work positioning means being mounted for rotation to bring different portions of the edge of the stock on the heel portion of the last into position for treatment.
29. In a shoe machine, work positioning means comprising a last support, a pair of jaws oppositely disposed for engaging and positioning the neck of the last, and a clamp member arranged to engage and hold shoe stock upon the bottom of the heel portion of the last, said parts being constructed and arranged to permit the last to be turned and to maintain the last in fixed angular relation.

tion to the support during its turning movement.

30. In a device of the class described, the combination of a last spindle, a plate mounted transversely on said spindle, a pair of members for engaging the sides of the last, said members being mounted on said plate for rectilinear movement toward or from the spindle, means tending to move said members away from the spindle, and means arranged to be engaged by the last for moving said members into engagement with the sides of the last.

31. In a device of the class described, the combination of a last spindle, a plate mounted transversely on said spindle, a pair of members for engaging the sides of the last, said members being mounted for movement on said plate toward or from the spindle, and a pair of levers pivoted on said plate and operatively connected with said members, said levers being arranged for operation through engagement with the last to effect a movement of said members toward the sides of the last.

32. In a device of the class described, the combination of a last spindle, a plate mounted transversely on said spindle, a pair of members for engaging the sides of the last, said members being mounted for movement on said plate toward or from the spindle, and a pair of bell-crank levers pivoted on said plate and operatively connected with said members, said levers having arms projecting into position to be engaged by the neck of the last to effect a movement of said members toward the sides of the last.

33. In a shoe machine, the combination of a work support mounted for substantially universal swinging movement and arranged to swing by gravity away from the machine, and means for partially counterbalancing said support to facilitate the presentation of the work to the machine.

34. In a shoe machine, the combination of

a work support mounted to swing by gravity both forwardly and laterally from the machine, and means for partially counterbalancing said support to facilitate movement of the support to operative position.

50

35. In a shoe machine, the combination with the machine frame, of a bracket on the frame, a work support pivoted on the bracket and extending forwardly therefrom, said support having an extension projecting under the bracket, and a spring plunger mounted in said extension and engaging the bracket for partially counterbalancing said support.

55

36. In a shoe machine, the combination with the machine frame, of a bracket on the frame, a work support pivoted on the bracket to swing by gravity both forwardly and to one side relatively to the machine, said support having an extension projecting under the bracket toward the rear and the opposite side with reference to the respective axes of movement of the support, and a spring plunger mounted in said extension and engaging the bracket for partially counterbalancing said support.

60

37. In a device of the class described, a pair of jaws oppositely disposed for engagement with the sides of a last, said jaws being slidably movable toward or from each other, and means connected to said jaws and arranged to be operated by engagement with the last for sliding said jaws toward the last.

65

38. In a device of the class described, a pair of jaws oppositely disposed for engagement with opposite sides of a last, said jaws being movable toward or from each other, and bell crank levers having pin and slot connections with said jaws and arranged to be operated by the last to move the jaws toward the last.

70

In testimony whereof we have signed our names to this specification.

LOUIS M. BROWN.

ALBERT A. MACLEOD.
